UNITED STATES PATENT OFFICE.

FREDERICK LEE HEUGHES, OF ROCHESTER, NEW YORK.

JOIST HANGER OR STIRRUP.

No. 818,689.

Specification of Letters Patent.

Patented April 24, 1906.

Application filed September 27, 1905. Serial No. 280,379.

To all whom it may concern:

Be it known that I, FREDERICK LEE HEUGHES, a citizen of the United States, residing at Rochester, in the county of Monroe 5 and State of New York, have invented certain new and useful Improvements in Joist Hangers or Stirrups; and I do hereby declare the following to be a full, clear, and exact description of the invention, such as will enable 10 others skilled in the art to which it appertains to make and use the same.

My present invention relates to improvements in joist hangers or stirrups intended to connect joists to beams; and it is intended to 15 provide a double hanger which will suspend a pair of joists one at each side of the beam and in which the strength of the hanger is not in any way dependent upon the uncertain strength of welding, but is directly governed 20 by the shearing strength of a known number of rivets, bolts, screws, or pins.

In the manufacture of double hangers it has heretofore been common to form part or all of the hanger of one or more pieces of material 25 in which the said pieces or the ends of the said piece are welded together, forming a welded joint, the strength of which weld is of very uncertain character and may vary greatly without the architect being able to 30 ascertain such variations or to locate any dangerous weakness. By having the parts connected by rivets, bolts, screws, or pins, as will be hereinafter described, the strength of the structure may be directly measured by 35 the shearing strength of any predetermined number of rivets, &c., and thus said strength will be positively known within reasonable bounds.

My invention will be understood by reference to the accompanying drawings, in which the same parts are indicated by the same letters throughout the several views.

Figure 1 is a perspective view showing the double hanger in full lines and the beam and 45 joists in dotted lines. Fig. 2 is a plan view of the hanger shown in Fig. 1, parts being broken away; and Fig. 3 is an end view of part of the device shown in Fig. 1.

The hanger consists of two straps A, each 50 made of a continuous strip of metal with a top piece a and dependent legs a', fitted to the size of the beam. These two straps are connected together by the stirrups B, which have a supporting-shelf b, side ribs b', which may 55 be tapered, as at b², and side flanges b³, secured by the rivets c to the legs a' of the

straps A. These side ribs b' may be perforated, as at b⁰, to spike the joist to the stirrup.

D represents a beam of any size or desirable construction, as the device is adapted for 60 use with any suitable form of beam or girder, whether made of metal, wood, or other material. The straps A may be perforated, as shown at b⁰, and spiked to the beam D, if desired. 65

Two joists E are indicated in dotted lines, one at each side of the beam D, one end of each being supported in one of the stirrups B. It will be obvious that the stirrups B may be raised or lowered by shifting the position of 70 the holes in the legs a' of the straps A.

The stirrups are made by punching out the center section of one leg of an angle-iron and bending the two remaining end sections of this leg at right angles to the notch. 75

It will thus be seen that I provide a joist-hanger which is provided with oppositely-disposed stirrups, each adapted to support a joist, on opposite sides of the beam. Moreover, the supporting-strips are made of a single 80 piece of metal without any weld, and the stirrups are secured to said straps by an adequate number of rivets, bolts, pins, or screws whose shearing strength can be accurately calculated. 85

The advantages of this construction are its strength, ease of manufacture, and inexpensiveness. The strength may be accurately calculated and provision made for increased weights by increasing the number of rivets, 90 bolts, pins, or screws used. Furthermore, the device may be made of any required size and out of flat iron bars and angle-irons, that can easily be purchased in the open market, which fact brings the expense down to a 95 minimum.

Having thus described my invention, what I claim, and desire to secure by Letters Patent of the United States, is—

1. A double joist-hanger comprising two 100 bent straps adapted to go over the beam, with depending legs, and stirrups each having a supporting-shelf with angle-iron sides made integral with said shelf, with rivets, bolts, screws, or pins connecting said angle-iron sides to said supporting-straps, substantially as described. 105

2. A double joist-hanger comprising two supporting-straps each composed of a flat piece of metal bent to fit the beam, and each 110 provided with depending legs, a pair of stirrups, one on each side, each provided with a

supporting-shelf, an upwardly-projecting rib integral with said shelf, and flanges projecting laterally from said ribs, with rivets, bolts, screws or pins securing said flanges to said 5 depending legs, substantially as described.

3. In a hanger, the combination of straps bent to fit a beam, and stirrups connecting the lower ends of said straps together, each 10 stirrup being formed of angle-iron with a notch cut out of one leg and then bent at

right angles at each end of the notch, and means for securing said stirrups to said straps, substantially as described.

In testimony whereof I affix my signature in presence of two witnesses.

FREDERICK LEE HEUGHES.
